CLAIM

The ornamental design for a two part sign holder assembly, as shown and described.

DESCRIPTION

FIG. 1 is a perspective view of the sign holder section of the two part sign holder assembly showing our new design; the track section has been omitted for purpose of disclosure; FIG. 2 is a left side elevational view thereof, with the right side elevational view being a mirror image thereof; FIG. 3 is a front elevational view thereof; FIG. 4 is a top plan view thereof; FIG. 5 is a rear elevational view thereof; FIG. 6 is a bottom plan view thereof; FIG. 7 is a perspective view of the track section, cooperating with the sign holder of FIG. 1, according to our new design; the sign holder section has been omitted for purpose of disclosure; FIG. 8 is a left side elevational view thereof, with the right side elevational view being a mirror image thereof; FIG. 9 is a top plan view thereof; FIG. 10 is a rear elevational view thereof; FIG. 11 is a front elevational view thereof; FIG. 12 is a bottom plan view thereof; and, FIG. 13 is a left side elevational view showing the sign holder of FIG. 1 assembled on the track of FIG. 7 and the assembly attached to a support surface. The support surface illustrated in dotted lines in FIG. 13 shows the environment of the two-part sign holder assembly according to the present invention and forms no part of the claimed design.
